COIN HOPPER

Wilson Marks Stewart, Ottawa, Ontario, Canada

Application April 4, 1952, Serial No. 280,539

4 Claims. (Cl. 194—97)

1

This invention relates to a coin hopper adapted for use with a coin selector of the type having a swingable gate.

A common type of coin selector has a swingable gate and a center plate. The swingable gate is normally biased towards the center plate and is held a predetermined distance therefrom by spacers or other suitable means so that a coin receiving opening is formed between the gate and the center plate.

When the coin selector becomes jammed with a spurious or counterfeit coin, it may be cleared of the coin by operation of means (which will be hereinafter described) which swings the swingable gate a predetermined distance away from the center plate. This action allows the jammed coin to drop out of the coin selector. An example of a coin selector of this type is described in U. S. Patent 2,292,628, issued August 11, 1942, in the name of Benjamin W. Fry.

It has been usual to provide a coin hopper or similar means to feed the coins to the coin receiving opening of the coin selector. In prior hoppers all of the sides thereof were fixed so that if two or more coins came to the bottom of the hopper together they could jam between the fixed sides. The rejecting feature of typical coin selectors was useful only for coins jammed in the selector and had no application for coins jammed in the hopper above the selector. Further, the jammed coins prevented any subsequent coins from reaching the coin receiving opening so that the entire apparatus with which the coin selector was associated was rendered inoperative. In order to put the apparatus back into operation 35 it was necessary to "open" it and remove the jammed coins from the hopper. This inconvenience was often enhanced when the persons who could "open" the apparatus were not readily available.

Often, a coin would enter the hopper at right angles to the converging sides thereof so that it would stand on edge across the mouth of the hopper. Sometimes, under these conditions the offending coin could be knocked out of this position and down into the coin receiving opening by pounding or jiggling the apparatus. At other times, particularly when the apparatus was very rigidly mounted, the offending coin remained in the "on-edge" position at the top of the hopper and no reasonable amount of pounding or jiggling would dislodge it.

It is the principal object of the present invention to provide a coin hopper wherein the size of the opening at the lower end thereof may be

2

momentarily increased so as to allow any coins jammed between the converging sides of the hopper to drop into the coin receiving opening and thereby be subject to the rejecting feature of a typical coin selector.

It is a further object of the invention to provide an arrangement whereby this increase in the size of the lower opening of the hopper is occasioned suddenly, and the opening returned 10 suddenly to its original size in such a way that a "fluttering" action is given to one side of the coin hopper.

I have found that the above objects may be accomplished by pivotally supporting one of the 15 converging sides at its upper edge and having its lower edge in resting engagement with the top of the swingable gate of the coin selector.

The invention will be more fully understood by reference to the attached drawings taken in 20 conjunction with the following detailed description.

Figure 1 is an elevation of a typical coin selector with a coin hopper according to the invention mounted thereon.

25 Figure 2 is a sectional view taken along the line 2—2 of Figure 1.

Figure 3 is a sectional view similar to that of Figure 2 but with the swingable gate shown in the rejecting position, and

30 Figure 4 is a sectional view taken along the line 4—4 and looking in the direction of the arrows.

In the drawings, 10 represents the center plate of a typical coin selector. A swingable gate 11 is mounted on a pintle 12 and biased towards the center plate 10 by means of a spring such as is shown at 13. Any suitable means (not shown) may be used to space the swingable gate 11 from the center plate 10 so as to form a coin receiving opening 14 (Figure 2). A dimple 15 is formed in the swingable gate 11. A finger plate 17 having a downwardly extending flange 18 is mounted on a pivot 19. Secured in the flange 18 is a protuberance 16 having a domed extremity which seats in the dimple 15. When pressure is applied to the finger plate 17 in a downward direction, it pivots about 19 thereby causing the protuberance 16 to come out of the dimple 15. This action forces the gate 11 to open against the action of the spring 13 so that the width of the coin receiving slot is increased (see Figure 3). Thus any spurious coins which may be lodged in the coin selector are allowed to drop into chutes, one of which is shown at 20. 40 45 50 55 The various features and parts of the coin se-

lector are standard and form no part of the present invention.

Associated with the coin selector is a coin hopper 21. The coin hopper 21 has a back plate 22 which is provided with forwardly directed flanges 23, 24. Pivotably supported in the flanges 23, 24 at 25, 26 is a sloping member 27. The lower edge of the sloping member 27 is in resting engagement with the top of the swingable gate 11.

If a plurality of coins are fed to the hopper 21 and happen to arrive at the mouth 28 together, they are liable to jam thereby preventing any further coins from reaching the coin receiving opening 14 of the coin selector. This was formerly a serious problem since prior coin hoppers employed fixed sides, and jiggling or shaking of the apparatus was liable to increase the jamming rather than relieve it. With the coin hopper 21 of the instant invention, any jammed coins are easily released by operation of the finger plate 17 which opens the swingable gate 11. The lower edge of the sloping member 27 which rests against the upper edge of the gate 11 will swing about its pivot 25, 26 thereby increasing the width of the opening of the mouth 28 so that any coins jammed therein are allowed to pass into the coin selector. This swinging action of the sloping member 27 occurs abruptly. When the finger plate 17 is released, the action of the spring 13 returns the swingable gate 11 to its original position (Figure 2) in an abrupt manner. Hence, a kicking action is given to the lower edge of the sloping member 27 by the gate 11 causing the sloping member 27 to "flutter" about its pivot points 25, 26. Any coins which are not released by opening the gate 11 are kicked out of their jammed condition by the fluttering action of the sloping member 27. Further, any coins which have come to rest on edge and are lodged between the back plate 22 and the sloping member 27 will be kicked up by the fluttering action and allowed to drop through the hopper 21 into the coin selector.

It is preferred (as shown in Figures 2 and 3) to provide the upper surface of the sloping member 27 with an arcuate curvature in the upper portion and a plane surface in the lower portion.

It will be understood, however, that the entire upper surface may have an arcuate curvature, or may be a plane surface; although neither of these arrangements are as satisfactory as that shown in the drawing.

What I claim as my invention is:

1. In combination with a coin chute of the type having a vertically pivoted forwardly swingable gate, a vertical coin hopper disposed above said coin chute and arranged to feed coins thereto; said coin hopper comprising a first member, two side members extending forwardly from said first member, and a rearwardly sloping member pivotally supported near its upper edge between said side members; the pivot point of said sloping member in each side member being positioned forward of said swingable gate and near the edge of said side member which is remote from said first member; the lower edge of said sloping member being in resting engagement with the upper edge of said swingable gate so that when said swingable gate is given a substantially sudden motion a fluttering action is imparted to said sloping member.
- 10 2. A combination as defined in claim 1 wherein the upper surface of said sloping member has a convex curvature.
- 15 3. The combination as defined in claim 1 wherein the upper portion of the upper surface of said sloping member has a convex curvature.
- 20 4. The combination as defined in claim 3 wherein the lower portion of the upper surface of said sloping member is substantially a plane surface.
